Primary Examiner — Michael A. Pratt

(74) Attorney, Agent, or Firm — DORSEY & WHITNEY LLP

(57) **CLAIM**

The ornamental design for a halfout for arrows as shown and described.

DESCRIPTION

FIG. 1 is an exploded perspective view of a halfout for arrows showing our new design;

FIG. 2 is a reverse exploded perspective view thereof;

FIG. 3 is an assembled perspective view thereof;

FIG. 4 is a reverse assembled perspective view thereof;

FIG. 5 is an exploded front view thereof;

FIG. 6 is an assembled front view thereof;

FIG. 7 is a right side elevation view thereof;

FIG. 8 is a left side elevation view thereof; and,

FIG. 9 is a section view, taken along the line 9-9 of FIG. 8, thereof.

The broken lines showing of mechanical elements are included for environmental purposes only and form no part of the claimed design.

1 Claim, 7 Drawing Sheets
